UNITED STATES PATENT OFFICE

HENRY L. SAMPSON, OF LOS ANGELES, CALIFORNIA

ELECTRIC CONTROL

Application filed January 10, 1927. Serial No. 160,137.

This invention has to do with an electric control suitable for use in connection with a switch or circuit breaker reclosing mechanisms, or other like or similar devices.

5 Circuit breakers are frequently used in situations where it is desirable for them to be automatically reclosed several times before being left in open position. Automatic breaker reclosing means have been developed 10 to meet this condition and, in general, such means usually include a mechanical or an electrical and mechanical device for actuating the breaker and an electrical control for governing the operation of such device. In 15 my co-pending application, entitled "Reclosing mechanism for circuit breakers," Serial No. 160,138, filed January 10, 1927, I set forth an electrically powered mechanical device for reclosing a breaker, while in this application 20 I set forth an electrical control suitable for use in combination with such device.

It is an object of my present invention to provide a simple, effective and reliable electrical control for a breaker reclosing mechanism, or the like.

The various objects and features of my invention will be best and more fully understood from the following detailed description of a typical form and application of the invention, throughout which description reference is had to the accompanying drawings, in which:

Fig. 1 is a view illustrating the device provided by my invention in its normal unactuated position;

Fig. 2 is a view similar to Fig. 1, showing the device partially operated or in an intermediate position;

Fig. 3 is a view similar to Figs. 1 and 2, 40 showing the device in the locked out position; and

Fig. 4 is a diagram illustrating the electrical connections provided by my invention.

My present invention is applicable, generally, to devices or equipment requiring manipulation or control similar to that required by certain circuit breakers or circuit breaker reclosing mechanisms. To facilitate an understanding of my invention, but without 50 limiting its scope or range of application, I

will make particular reference to the invention as applied to or used in connection with a circuit breaker reclosing mechanism, and in this connection I will state that the present invention may be advantageously employed 55 in connection with a reclosing mechanism such as I set forth and claim in my above mentioned co-pending application.

The device provided by my present invention includes, generally, an operating member 60 10, for connection with a circuit breaker or reclosing mechanism, a movable contact 11, operable from the operating member 10 through a control member 12, a stationary contact 13 connected with an alarm 14 and 65 arranged to co-operate with the contact 11, a stationary contact 15 connected in the operating circuit to the reclosing mechanism, a movable contact 16 and a stationary contact 17 arranged to co-operate in controlling the circuit to the releasing means 18, a movable contact 19 and a stationary contact 20 arranged 70 to co-operate in controlling the circuit to the reclosing mechanism and various other parts, the details and functions of which will be 75 hereinafter set forth.

The operating member is in the form of an arm pivotally mounted on a pin 25, carried by a frame plate 26. The member 10 is adapted to be oscillated between what I will 80 term a down position, as is shown in Fig. 1, and an up position, as is shown in Figs. 2 and 3. An operating connection is provided between the member 10 and a suitable movable part, either of the circuit breaker or the reclosing mechanism. The connection may be made through a rod 27, or other suitable means. I have eliminated from the disclosure any part of the circuit breaker or reclosing 85 mechanism, as such devices are familiar to 90 those skilled in this art and need no detailed explanation. It will be sufficient to state that the operating member 10 is operatively connected with the circuit breaker or its reclosing mechanism so that the member 10 is in the 95 down position when the breaker is closed and is in the up position when the breaker is open. The exact form of connection used in any particular case will depend upon the form or type of breaker reclosing mechanism. 100

The movable contact 11 is carried on one end of a lever 30 pivotally mounted on a pin 31 carried by the frame 26. The other end of the lever is provided with a head 32 which 5 co-operatively engages the control member 12. The contact 11 is carried on a spring arm and is movable in one direction from its normal position to engage the contact 13, and in the other direction to engage the contact 15. 10 The control member 12 is in the form of a disk rotatably mounted on the pin 25 adjacent the operating member 10. The disk has a cam part which co-operates with or is engaged by the head 32 of the lever 30. The 15 cam part is provided at one end with a shallow depression 34 to receive the head 32 when the parts are in the normal position and at the other end with a deep depression 36 to receive the head 32 when the device has been 20 completely and finally operated. The middle or intermediate part 34^a of the cam is such as to hold the lever 30 in position where the contact 11 engages the contact 15. The cam part is so designed with reference to the lever and 25 its head, that the contact 11 is held in an intermediate or neutral position between the contacts 13 and 15 when the head 32 is in the shallow depression, engages the contact 15 when the head 32 is in engagement with the 30 middle part of the cam, and engages the contact 13 when the head 32 is in the deep depression 36. The parts are related so that the contact 11 is in the neutral position when the device is in its normal unactuated position, is 35 in engagement with the contact 13 when the device is completely and finally actuated, and is in engagement with the contact 15 when the device is in any intermediate or partially actuated position. The control member is normally urged in the direction opposite to that 40 indicated by the arrow in Fig. 1, through the action of a spring 37 which has one end attached to the pin 25 and the other end attached to the control member. 45 The operating member 10 carries a spring pressed pawl 38 which co-operates with a series of notches 39 in the periphery of the control member to cause rotation of the control member with the operating member when the 50 operating member is moved from its down position to its up position. A control pawl 40, actuated by a spring 41, is arranged to co-operate with a second series of notches 42 provided in the periphery of the control member to catch and hold the control member against return rotation upon its being advanced through the action of the pawl 38. The pawl 38 is provided with a tail part 38^a which co-operates with a projection 42^a so 55 that it is lifted out of engagement with the series of notches when the operating member 10 is in the down position, but is immediately released to engage the notches when the operating member starts its upward movement. 60 In the particular construction shown in the 65

drawings, the device is adapted to energize or close the circuit to the reclosing mechanism three times and then leave the circuit permanently open. In this case, the control member includes four notches 39. It being 70 obvious that the notches 39 and 42 in the control member are properly related with reference to the cam part, which operates the lever 30, so that the head 32 of the lever 30 is in the shallow depression when the operating 75 member is in position with the pawl ready to engage the first notch 39 while the deep depression 36 receives the head when the pawl 38 has moved the operating member after engaging the last notch 39.

The means 18, provided for releasing the holding pawl 40, includes a heat coil 44 and a movable element associated with the coil and connected with an arm 46 extending from the pawl. The movable element 45 is of the type 80 found in thermostats of various kinds and is adapted to move, as indicated by the arrow in Fig. 1, upon the coil 44 being energized long enough to warm the element. The connection between the movable element 45 and the arm 46 may include a connecting rod 48 carried by the arm and extending through an opening in the element. The rod is provided with a stop 50 adapted to be engaged by the 85 element so that the arm is moved with the element, although the arm can be moved manually, independently of the element. In practice, the rod 48 can be extended to any suitable point where it will be convenient to 90 operate.

The contacts 16 and 19 are carried on spaced spring arms 51 and 52, respectively, and are adapted to be moved from the operating member 10 through a pivoted lever 90 having one end 53 operatively connected with the member 10 and the other end 54 arranged between the arms 51 and 52. The end 53 of the lever extends into a suitable recess 56 in the operating member 10 so that the lever is moved between the position shown in Fig. 1 to that shown in Fig. 2 upon the member 10 being moved between the down position and the up position. When the operating member 10 is in the down position, the end 54 of the lever 90 is in position where it engages the arm 51 to hold the contact 16 in engagement with the contact 17. When the lever is in the other position, as shown in Figs. 2 and 3, the end 54 of the lever engages the arm 52 to hold the contact 19 in engagement with the contact 20.

The electrical connections provided with the parts which I have above described result in the control of a motor M, or the like, the heat coil 44, and an alarm 14 from the operating member 10. We may consider energy supplied from any suitable source such as a generator G. One side or pole of the generator is connected with the contact 11 through a line 60, while the other pole is connected directly with one side or pole of the 110 115 120 125 130

motor M through a line 61. The connection between the contact 11 and the other pole of the motor M is completed through the contact 15, a connection 62 connecting the contact 15 with the contact 19, the contact 20, and a line 63 connecting the contact 20 with said other pole of the motor. It will thus be seen that the motor is energized only when the contacts 11 and 15 and the contacts 19 and 20 are together. Such condition is illustrated in Fig. 2 of the drawings, which positioning of the device occurs when the operating member 10 is up and the breaker is open. I will term this circuit between the generator and motor the main circuit.

The alarm 14 is connected with the line 61 from the generator through a connection 65 and is connected from the line 60 through contact 13 and a line 66. I have, for sake of example, illustrated a simple bell alarm operated from the generator circuit through transformer T. The alarm circuit, as I will term it, is closed only when the contact 11 is in engagement with the contact 13.

The heating coil 44 has one terminal connected with the line 61 from the generator by a suitable connection 70 and its other terminal connected with the contact 17 by a connection 71. The contact 16, which cooperates with the contact 17, is electrically connected with the contact 19 which, as before stated, is connected with the contact 15 by the connection 62. With this arrangement, the coil 44 is energized only when the contacts 11 and 15 and the contacts 16 and 17 are together. The circuit to the coil 44 will be termed the release circuit.

In operation, the various parts of the device are normally in the position illustrated in Fig. 1, in which case the head 32 of the lever 30 is in the shallow depression 34 so that the contact 11 is spaced from both the contacts 13 and 15. Under this condition, all circuits are open. Upon the breaker opening and the operating member 10 being moved to the up position, as shown in Fig. 2, the cam part of the control member moves the lever 30 so that the contact 11 engages the contact 15 and the lever 90 is moved to position where it causes the contact 19 to engage the contact 20. The movement of the control member to cause operation of the lever 30 is caused by the pawl 38 engaging the first notch 39. With the parts in this position, the contacts 11 and 15 and the contacts 19 and 20 are together and therefore the main circuit is closed and the motor M is put in operation. The parts will remain in this position and the main circuit to the motor will remain closed until the motor has functioned to effect reclosing of the breaker, at which time the operating member 10 will return to its down position. The control member will be held by the pawl 40 in the position to which it was moved by the pawl 38. In this case, the lever

90 will have returned to the position shown in Fig. 1, while the lever 30 will remain in the position shown in Fig. 2, thus causing the contacts 11 and 15 and the contacts 16 and 17 to be in engagement, under which condition the release circuit is closed so that the heating coil 44 is energized. If the operating member 10 remains in the down position, or in other words, if the circuit breaker remains closed, the connection just described will continue until the heating coil causes movement of the element 45 so that the pawl 40 releases the control member 12, allowing the control member to be returned by the spring 37 to its normal position, shown in Fig. 1, in which positioning of parts the lever 30 holds the contact 11 out of engagement with the contacts 13 and 15 and all circuits are open. However, if the breaker does not remain closed, but is again thrown open, the operating member 10 will again move from the down position to the up position, in which case the pawl 38 engages the second notch 39 and causes the control member to rotate or advance. The parts then will be in the position shown in Fig. 2, except that the control member will be one notch advanced, in which case the main circuit is closed so that the reclosing mechanism functions to again reclose the breaker. This repeated reclosing of the breaker or closing of the main circuit to the motor M will continue until such time as the breaker remains closed or the control member has rotated to a position where the head 32 drops in to the deep depression 36, which operation allows the lever 30 to move the contact 11 out of engagement with the contact 15 and into engagement with the contact 13. With the contact 11 in engagement with the contact 13, the main circuit and the release circuit are open while the alarm circuit is closed and thus serves to notify an attendant that the control has functioned its specified number of times without the breaker staying closed. It will be obvious that the number of times the main circuit is reclosed will depend upon the design and proportioning of the control member 12. By providing a suitable cam part and arrangement of notches on the control part, the main circuit can be reclosed the desired number of times. By providing interchangeable control parts of different designs, the operation of the device can be readily changed as desired.

Having described only a typical preferred form of my invention, I do not wish to limit myself to the specific details set forth, but wish to reserve to myself any changes or variations that may appear to those skilled in the art or fall within the scope of the following claims:

Having described my invention, I claim:

1. A control of the character described including a main circuit, a release circuit, a contact in said circuits operable to closed posi-

- tion, a second contact in the main circuit operable to closed position, a third contact in the release circuit operable to closed position, an operating member operable between a normal and an actuated position and connected with the second contact to hold it in closed position when actuated and connected with the third contact to hold it in closed position when unactuated, a control member adapted to be actuated by operation of the operating member, means whereby the control member operates to hold the first mentioned contact in closed position during a predetermined number of operations of the control member, and a releasable retaining device operable to hold the control member actuated, said device being operatively connected with the release circuit to be released upon said circuit being closed a predetermined length of time.
2. A control of the character described including a main circuit, a restoring circuit, a contact device normally open and connected in the main circuit and the restoring circuit, a second contact device in the main circuit, a third contact device in the restoring circuit, an operating member movable between a normal position and an actuated position, means operatively connecting the operating member and the first mentioned contact device whereby the first mentioned contact device is held closed during a predetermined number of operations of the operating member, said means including a cam device advanced by operation of the operating member and a lever engaging the cam device and operatively connected with the said contact device, and means whereby the second contact device is closed when the operating member is in the actuated position and the third contact device is closed when the operating member is in the normal position, said last mentioned means including a lever operated by the operating member and engaging the second and third contact devices to actuate them.
3. A control of the character described including a main circuit, a restoring circuit, a contact device normally open and connected in the main circuit and the restoring circuit, a second contact device in the main circuit, a third contact device in the restoring circuit, an operating member movable between a normal position and an actuated position, means operatively connecting the operating member and the first mentioned contact device whereby the first mentioned contact device is held closed during a predetermined number of operations of the operating member, said means including a rotatable control part, a lever operatively connected in the control part with the contact device and a ratchet connecting said part and the operating member whereby the said part is advanced by successive operations of the operating member, and means whereby the second contact device is closed when the operating member is in the actuated position and the third contact device is closed when the operating member is in the normal position.
4. A control of the character described including a main circuit, a restoring circuit, a contact device normally open and connected in the main circuit and the restoring circuit, a second contact device in the main circuit, a third contact device in the restoring circuit, an operating member movable between a normal position and an actuated position, means operatively connecting the operating member and the first mentioned contact device whereby the first mentioned contact device is held closed during a predetermined number of operations of the operating member, said means including a control disk having a cam part, a lever operatively connected with the contact device and engaging the cam part of the disk, and ratchet means between the cam part and operating member whereby the cam part is advanced by successive operations of the operating member, and means whereby the second contact device is closed when the operating member is in the actuated position and the third contact device is closed when the operating member is in the normal position.
5. A control device of the character described including a main circuit, a release circuit, a contact device normally open and in the main circuit and release circuit, a second contact device in the main circuit, a third contact device in the release circuit, an operating member, a control member adapted to be advanced by actuation of the operating member, thermostatic means controlled by the release circuit operable to releasably hold the control member in its advanced positions, means whereby the first mentioned contact device is held closed during a predetermined number of operations of the control member, and means whereby the second contact device is closed when the operating member is in an actuated position and the third contact device is closed when the operating member is in its normal position.
6. A control device of the character described including a main circuit, a release circuit, a contact device normally open and in the main circuit and release circuit, a second contact device in the main circuit, a third contact device in the release circuit, an operating member, a control member adapted to be advanced by actuation of the operating member, thermostatic means controlled by the release circuit operable to releasably hold the control member in its advanced positions, means whereby the first mentioned contact device is held closed during a predetermined number of operations of the control member, and means whereby the second contact device is closed when the operating member is in an actuated position and the third contact device is closed when the operating member is in its normal position.

in its normal position, said thermostatic means including a ratchet device engaging the control member.

7. A control device of the character described including a main circuit, a release circuit, a contact device normally open and in the main circuit and release circuit, a second contact device in the main circuit, a third contact device in the release circuit, an operating member, a control member adapted to be advanced by actuation of the operating member, thermostatic means controlled by the release circuit operable to releasably hold the control member in its advanced positions, means whereby the first mentioned contact device is held closed during a predetermined number of operations of the control member, and means whereby the second contact device is closed when the operating member is in an actuated position and the third contact device is closed when the operating member is in its normal position, said thermostatic means including a ratchet device engaging the control member and a heating coil connected in the release circuit.

8. A control of the character described including a main circuit, a release circuit, a contact device normally open and connected in said circuits, an operating member, a control member, a ratchet connection between the operating member and control member whereby the control member is advanced by actuation of the operating member, means whereby the first mentioned contact device is held closed during a predetermined number of advances of the control member, means whereby the second contact device is closed when the operating member is in an actuated position and the third contact device is closed when the operating member is in the normal position, a ratchet device for releasably holding the control member in advanced positions, and a thermostatic device for releasing the said last mentioned ratchet device including a heating coil connected in the release circuit.

In witness that I claim the foregoing I have hereunto subscribed my name this 7th day of December 1926.

HENRY L. SAMPSON.
